UNITED STATES PATENT OFFICE.

HERBERT LAWTON COFFIN, OF NEW YORK, N. Y.

AIRPLANE.

Application filed December 3, 1919. Serial No. 342,047.

To all whom it may concern:

Be it known that I, HERBERT LAWTON COFFIN, a citizen of the United States, residing in New York, in the county of New York and State of New York, have invented certain new and useful Improvements in Airplanes, of which the following is a specification.

This invention relates to that class of machines for aerial navigation which are now usually designated as air-planes, and it is applicable to heavier-than-air machines, in general. The present improvements relate more especially to the construction and equipment of the wings for airplanes; and a principal object is to furnish an airplane-wing of strong, simple and effective construction and comprising improved means for use in guiding and balancing the airplane while in flight.

One object is to provide improved means for securing an effective lifting action and effect, and to do this without any interference,—as by a tilting or other device projectable above the upper (or top) surface of the wing,—with the force and regular flow of air over and near to the upper surface, and thereby avoid the production above the wing of obstructive air currents which would tend to counteract the wing-lifting effect.

A further feature and object is to furnish such an airplane wing in which the usual ailerons are not required, and which shall be provided with an elevating or balancing means organized and positioned for so acting upon the wings as to lift the same by the action of air currents, and which when not in use for such purpose are mid-zone portions of the upper and lower surfaces of the wing and thus operate normally as integral parts of such surface as regards the gliding of the wings through the air.

Further objects and advantages are pointed out and explained in the course of the following description.

In the accompanying drawings forming a part of this specification, Figure 1 is a perspective view drawn on a small scale, for showing the arrangement of an airplane having the upper wings thereof made in accordance with the present invention.

Fig. 2 is a plan view on an enlarged scale, of one said wing; and, Fig. 3 is a cross-sectional view of this wing, drawn on a scale corresponding to that of Fig. 2.

Fig. 4 is a partial section on a much larger scale, for showing the mid-zone portion of the wing, including the panel-system, and is illustrative of the mode of operation of the invention.

Fig. 5 is a view similar to Fig. 3, and is drawn to illustrate, in a diagrammatic manner certain features of the mode of action, as hereinafter more fully explained.

Figs. 6 and 7 show one modification of the mechanism of the wing, and illustrate the mode of action thereof.

Figs. 8, 9 and 10, are series of diagrams explanatory of certain features and functional relations involved in the operation of the wing mechanism.

Fig. 11 is a view illustrative of a modified panel-actuating means.

Similar characters designate like parts in all the views.

The present improvements, are herein shown applied to that class of airplane wings in which a frame is enclosed between upper and lower coverings forming the external surfaces of the wing. Said frame, in order to secure sufficient rigidity, is usually, in present practice, built up of longitudinal bars, or beams, as B¹, B², combined with several cross-bars,—usually as indicated by dotted lines at H¹, H², (Fig. 2), and with a border member, as J, extending (preferably continuously) along the sides and around the outer end, E, of the wing. Also, these several frame members, besides being strongly connected by usual fastenings (not shown), are held in place and strengthened by diagonal tires or braces, which may be arranged in the well-known manner indicated by the dash-lines G¹, G², in Fig. 2.

In the mid-zone part of the wing,—this being also the deepest portion thereof,—a panel-chamber, C, is formed, for receiving a panel-system which comprises an upper and a lower panel and operating means therefor. One said panel, as P¹, when in closed position, is in line with and forms a part of the upper wing-surface; and another said panel, P², is in line with and forms a part of the lower wing-surface. Said upper panel, P¹, is shown of a relatively narrow width, and the lower panel, P², is much wider, so that the rearward edge, as 27^a, of the lower one extends to a considerable distance rearwardly of the upper one,—see Figs. 3, 4,—and, to provide for this arrange-

ment of the panels, said chamber C is made widest on the underside thereof, and has a rearward wall, 24, which is inclined downwardly and rearwardly, preferably on a low angle as illustrated, and through a distance, D, greater than the depth of the wing.

When the upper surface panel, P¹, is in closed position, (Fig. 3), the upper wing-surface becomes continuous and thus provides for a free and unobstructed flow of air over and contiguous to the entire width of the wing; but, when said panel P¹, is lowered as in Fig. 4, said air current on passing the point 23, expands downwardly into the space 15 at S below the line L, thereby decreasing the air-pressure upon the panel, P¹, and thus the capacity of the upper wing surface to resist upward movement is materially reduced. Also by reason of the direction of the air-currents and the positions and peculiar arrangement of the current-guiding surfaces, (these including the incline 24) an area represented in width by the distance 25, is practically subtracted from the full area of said 20 upper wing-surface, thereby further reducing said resistance thereof to upward movement when in flight. Thus said devices and construction may be said to constitute means for reducing the upward-movement-resisting 25 surface of the wing concurrently with the actuation of said lower panel, P², in a direction to increase the lifting effect thereof.

A further feature of practical importance (more clearly observed in Fig. 4) consists 30 in the attachment, or connecting of the lower panel P² to the upper panel P¹, so that in swinging these panels downward, the rearward edge 27^a of said lower panel, follows in a curved line, 28, which is concentric with the 35 joint or axis 23 of said upper panel; as a result, the opening, 26, is materially increased, as compared with the width such opening would have if said lower panel should be hinged at the point 29^b; thus a relatively 40 large outlet space is provided for the air current which flows downwardly against the inclined wall or lifting surface 24. To provide for this mode of action, the forward edge 27^c of said lower panel is preferably 45 arranged to swing above the rearward edge 29^a of the forward portion 29 of the lower wing-surface; this arrangement also operates to narrow the acting area of the surface of said panel P² in proportion as this 50 55 is swung downwardly from its closed position in Fig. 3 to its open position in Fig. 4.

The panel structure may comprise a light frame-work (herein only partially shown) suitable in arrangement and strength for 60 carrying the panel-sheets, as P¹, P², and the inclined rearward wall-surface P³; each of these three sheets, or surfaces, may be made of such kinds of material,—these including metal, wood or fabric,—as usually used or 65 adapted to be employed, for the lower and

upper coverings or surfaces of the wing itself. This panel-frame is herein indicated as being hinged at 23 to a member or bar, of the wing-frame in some convenient manner. In practice, said panel-surfaces P¹, P², 70 and said wall-surface P³, may be made of a single piece of such a fabric or material, this being folded over said frame-work and fastened thereto; the panel-system when thus organized and covered, is operable upon said axis, 23, as a single member of the wing, and when fully closed (Fig. 3), the wall surface P³ thereof lies near to the inclined wall 24 of the wing.

The connected panels, P¹, P², may be conveniently operated by means of a control-apparatus substantially such as commonly used on air-planes for similar purposes, (not herein shown), a suitable connection being made by a wire, w, attached to the lower panel P², whereby to pull this panel down from its zero position in Fig. 3, into a working position, Fig. 4. For closing the panels, when the wire w is relaxed, a spring, as R, of suitable power may be connected to the lower panel at R¹, and arranged (preferably,—as herein shown,—within the interior space of the wing), to react against an abutment, as 29^c; but other panel opening and closing means may be employed, if desired, instead of those here described. When the panels are fully closed while the airplane is in flight, they normally tend to remain closed independently of said spring, R, owing to the larger area of, and greater air-pressure under, said lower panel P² as compared with said upper panel P¹.

Said complete panel systems, as will now be evident, each comprises three surfaces, as P¹, P², P³, each having a different position and function, not only in the panel-system itself, but also as to the coactive relations thereof to the adjacent parts of the main surfaces of the wing. Each panel system when closed constitutes, in effect, a part of the upper and lower wing surfaces, and is inoperative otherwise than as a part of the wing; but when lowered,—see Fig. 4, and the description thereof,—each panel-system is operative for raising (but not for lowering) the wing during flight. In order, therefore, to balance or otherwise properly control the airplane in flight, only one of the two panel systems,—as P⁷ or P⁸, Fig. 1,—should be depressed at one time; this mode of operation may be readily accomplished by suitably arranging the connecting wires, as w, to the usual centrally located control lever,—not herein shown. When the two panel-systems, one in each of a pair of oppositely-disposed wings, are depressed at the same time, it is evident that the normal effect will be to make the airplane climb more rapidly.

The diversion of air from the upper surface of the wing, before this air reaches the

rearward part of that surface, tends to reduce the air pressure in that rearward zone, and thereby assists the uplifting of the wing by the increased pressure below the wing. The air so diverted is directed into the normal low-pressure area, or zone, that is directly in the rear of the pressure-panel P^2 when this panel is depressed, and thus supplies air to counteract the otherwise normal

10 tendency to the forming of a condition naturally operating against said pressure-panel or mid-zone, panel of the wing. Thus I secure a single stream of air down through the mid-zone and wholly in a position rearward 15 of all the movably-supported members when these are shifted into a functioning position.

The described arrangement and mode of action of said lower panel P^2 , while it may require a greater arc of movement of said 20 lower panel P^2 than might otherwise be necessary, has the advantage that by thus bringing the panel surface to a greater angle, the lower air-current approaching at 30 (Fig. 4) is more positively "banked up" 25 forward of said panel, and thereby extends the zone of pressure-increase, or plus-normal pressure, farther forward, so that a favorable positioning of the area, or center, of the wing-lifting effect is naturally obtained; 30 also, by the relative widening of outlet 26, as described, a relatively larger flow of air against the incline 24, is secured, and a more complete filling to, or nearly to, normal pressure, of the low-pressure zone normally 35 formed at 31 (Fig. 4) rearward of the panel P^2 when this is depressed during flight, into its wing-lifting position.

Said wing-lifting effects, by the means and action described, are brought into locations on either side of a vertical line, V , which represents the usual line of balance of the airplane; in flight, of course, this line will move forwardly and backwardly, will fluctuate, to some extent under the rapidly 45 changing conditions. Forward of such position line V , (see Fig. 5), there is a plus-normal pressure, at 32 underneath a normal pressure, at 33, thus producing on the forward part of the wing, a lifting effect indicated by arrow 34, Fig. 5. And, rearward of said line V , there is produced at 35 a compensated pressure which is about equal to normal pressure, and is located directly 50 below an area of minus-normal pressure at 36, thus producing on the rearward part of the wing, a lifting effect indicated by the arrow 37. Thus the two lifting effects,—represented, respectively, by arrows 34, 37,—are coactive, one forward and the other 55 rearward of line V , in a manner for conserving the proper balance of the airplane.

As further illustrated in Figs. 8, 9, the conduit wall P^3 of the panel-system may be 60 considered as being pivoted to the wing at 65 23, and thus bodily shiftable from a closed

position and by a swinging movement to successive open positions, as 38, 39, 40, Fig. 8. In position, 38, the wall P^3 lies close to the fixed inclined wall 24 of the wing, and when swung downwardly,—thereby moving 70 both ends in the same direction at the same time,—the lower end 27^a moves more rapidly than the upper end 41, thus producing a conduit channel or flue, S , (Fig. 9), bounded by the two plain and diverging wall surfaces, P^3 , 24, and having at the lower end a width, as 26, materially greater than the width, as 25, at the upper end, so that the degree of taper of the conduit or channel increases, or is progressively amplified in 80 proportion to the extent to which the width thereof is increased. This form and mode of action of the channel S is deemed to be particularly favorable for effectively directing the transfer of air from the normal-pressure area, at 33, above the wing to the low-pressure area otherwise normally formed at 35, and already described, for thereby, through a compensating action, overcoming the effect normally due to the loss of air in 90 said area 35. In the channel S , the flow of air seems to correspond in principle with the flow in the discharge end of the well-known "Venturi" tubes. The stream of air in said channel S , it should be noted, is 95 drawn from a point forward of said balance-line V , and is discharged into a space rearward of the lower panel-zone.

In a preferred construction thereof, as herein shown, (see Fig. 10), the line of the channel-wall 24, if continued as at 24^b, passes the wall-pivot 23 by a distance 24^c, substantially, or very nearly equal to the depth of the wing, so that said distances may be said to correspond; similarly, the width of the wall 24 (from point 43 to point 44) is in correspondence with the prolongation 24^b, from point 44 to the point 45, where the distance by line 24^c (from the pivot 23) is at right-angles to such prolongation 24^b. From this comparison it will be seen how the pivot point 23 is here shown on a line, 46, midway of the angle subtended by the line of the channel-wall 24 and the line of the lower panel P^2 , thus producing a specific arrangement which has symmetrical features and is well proportioned for effective action.

By means of the present improvements, the lifting effect required for balancing is produced, of course, by an increase of air-pressure on the underside of the wing, but I accomplish this while avoiding an increase of air-pressure over any portion of the upper surface of the wing. The air currents passing above the wing, as at arrow 47, (Fig. 5), glide along smoothly and tend to spread downwardly,—owing to the inclination of the wing as a whole, (see Fig. 3), to its line of forward movement,—thereby

normally reducing the air-pressure upon said upper wing-surface, and this effect is further increased by the diversion downwardly through the guide-channel S of a portion of such over-wing air currents. This diversion, it should be noted, is accomplished without interposing any obstructive means or device into the normal path of said over-wing upper currents, and 10 without tending to form any eddy-currents, or irregularity of flow therein.

Thus I avoid the objections incident to the ordinary pivoted vanes as heretofore used in mid-zone wing-openings, whereby 15 such upper currents are unavoidably divided and confused in their action, thereby producing higher air pressures in some areas above the wings and so counteracting in large measure the lifting effect of any increase of air pressure below the wings. Especially, I avoid the diversion by any current-intercepting or projective vane or edge, of any stream of air from above the wing and into a zone of increased air pressure below the wing; and, contrary to that 20 common practice,—in which two such zone-pressures operate in a conflicting manner,—I only cause one air-current to flow downwardly, and this current is guided directly 25 into an under-wing zone of relatively low-pressure which serves as an active but non-interfering means for drawing such current, as by a suction, away from and out of the main air-current, flowing over and contiguous to the wing. Also, I divert high pressure air from the top of the wing to the underside thereof, thereby increasing the pressure under the wing (and rearward of said panel P^2), for lifting effect. Thus I 30 secure, with a high efficiency and a minimum of friction and loss of power, a normal, harmonious and complete coaction of all the means and surfaces employed, and of all the air currents, including the single 35 one thus especially produced and utilized.

Instead of arranging the two panels, P^1 , P^2 , to be swung in unison as herein illustrated, they may be arranged in some instances to be operated concurrently but with 40 different relative angular rate of movement; this further improvement, although broadly within the purview of my present invention, is not specifically claimed herein, but is intended to constitute in part the subject matter of a separate application to be 45 concurrently pending herewith.

In the construction of the wing shown in Figs. 3 and 4, the frame-work has the interior space thereof,—excepting the panel-system-chamber in a mid-width zone thereof,—covered in by upper and lower facings, or surfacings, as N, N^1 , which are separated, and which properly may consist of either metal or fabric, or other suitable 50 surfacing sheets or layers, and these may

be applied and secured, and drawn, taut, in accordance with a well-known practice.

In that longitudinal portion of the wing, (as the length-zone 48, between lines 49, 50, Fig 3), in which said chamber, C, is located, 70 the continuity of said upper and lower surfacings is interrupted by said chamber or chamber-space, so that said upper surfacing comprises a forward zone, and surface or area N^3 and a rearward zone and surface 75 or area N^4 ; similarly the lower surfacing comprises a forward zone and under-surface, N^5 , and a rearward zone, and under-surface N^6 . Thus there are in said length-zone 48, forward and rearward wing-zones 80 corresponding to said forward and rearward surfaces, on both the upper and the lower surfaces of the wing; and, since the panels P^1 , P^2 , at their forward edges 51, 52, operably join with the rearward edges 85 of said forward zone-surfaces N^3 and N^5 , respectively, of the wing, therefore said panels P^1 and P^2 , when in their closed position, Fig. 3, constitute rearward continuations,—which are also, in a sense, aligned 90 continuations,—of said upper and lower forward wing-zones and surfacings, N^3 , and N^4 , respectively, and thus connect, across said mid-width zone, as by a substantially uninterrupted and aligned surface the said forward and rearward zone-areas of the 95 upper and lower wing-surfaces, respectively.

A modified construction or embodiment of the invention is illustrated in Figs. 6 and 7. 100 In this instance, the forwardly-joined panels P^1 , P^2 , (of the panel system) are operated in the same manner as in the principal views (Figs. 2 to 5), but the coacting downwardly and rearwardly inclined wall or surface, 24^a, is here shown arranged on a supplemental panel-system, P^6 which is operably connected at its rearward edge, 53 to the narrow rearward zone 54, of the wing. The main panel system, comprising the surfaces P^1 , P^2 of the under-lapping panel and P^{12} , P^{13} of 105 the over-lapping panel, and the guide wall or face 24^a, is or may be the same in the construction in Figs. 6 and 7 as it is in the arrangement of Figs. 2, 3, and 4; the position of the coacting guide-wall 24 in these latter 110 views is shown by the line 55 in Fig. 6.

In said view, Fig. 6, said guide-wall 24^a is not only movably supported, but is also reversely-operable in relation to panel system P ; when the latter airplane member, P , is lowered the panel-member P^6 is raised, so that these two airplane-members, P and P^6 are swung, or partially rotated, about axes, as 53, 23, positioned on the reverse sides thereof, respectively, these two rotative movements being, however, in the same direction, as indicated by the circular arrow-lines 56 and 57, drawn around said axes, respectively. The members P and P^6 may be 115 operated in a convenient manner by any 120

suitable rods, or connections as for instance, by rods 58 and 59 connected to arms on a rocker-shaft, 60, in the manner shown; this shaft may be supported on the lower wing 5 (in the case of a bi-plane) or otherwise, and may be actuated by a handle, as 61, or by other well-known shaft-position-controlling means, (not herein shown).

The additional improvements herein illustrated in Figs. 6 and 7 while deemed to be within the purview, broadly, of my present invention, are not specifically claimed herein, but will constitute in part the subject-matter of a separate application to be 10 currently pending herewith.

For the purpose of securing a high degree of efficiency in the practical operation of the system herein set forth, it is deemed to be 20 advantageous to have the zones, or zone-portions comprised in the wing transversely thereof arranged and proportioned in a manner substantially as follows:—The forward zone, Z^1 (Fig. 3), has a fixed relation to the wing, and at its rearward edge has a 25 depth in accordance with the vertical distance between the spaced-apart upper and lower surfaces of the wing. The mid-zone Z^3 , is hinged (that is, operably connected) at its forward edge to the rearward edge of 30 said forward zone, the axis thereof being preferably (for reasons elsewhere herein stated) close or contiguous to said upper wing-surface. The rearward zone Z^2 is 35 shown in Fig. 3 as having a fixed relation to the wing; but in some instances, as in Fig. 7, (and particularly when applied to large airplanes) this wing-zone may be operably-supported, as already explained. Said mid-zone Z^3 underlaps the rearward zone Z^2 by 40 a considerable distance, which is preferably about one-third, or between one-fourth and one-half, of the width of the mid-zone, and, also, greater than the spaced-apart distance (as 57, Fig. 4) of said upper and lower wing 45 surfaces, thereby securing a low angle, as for instance, an angle of less than 45 degrees of the inclined walls or surfaces N^4 and 24, as clearly indicated in the drawings.

Instead of connecting the two panels P^1 , and P^2 , (as described in connection with 50 4), for actuation of the upper panel P^1 by or from the lower panel P^2 , each of these panels may be actuated independently of the other. This arrangement is illustrated in 55 one form thereof in Fig. 11, where one ordinary rock-shaft, 63, has an arm 64, operably connected by a rod 65 to said lower panel; and, a second rock-shaft, 66, similarly has an arm 67 operably connected by rod 68 to 60 the upper panel P^1 . Said rod 68 may pass through a small opening at 69 in the lower panel, when the use of this detail shall be found convenient. In practice, of course, the shafts 63, 66 may be located in any 65 convenient or suitable position on the frame-

work of the airplane, and the panel-actuating connections 65, 68 may be of such character and length as found necessary in any particular instance; also, said shafts 63, 66, may be extended to such a length as required, 70 and be manually or otherwise operated by ordinary or suitable control means, (not herein shown).

When thus or similarly arranged, (Fig. 11) the lower and supportive panel may be 75 lowered, as indicated at P^2 , while the upper and non-supportive panel P^1 remains closed, as there shown by solid lines; also, the upper panel may be swung down, as indicated by dotted lines at P^{10} , whether said lower panel 80 be then in a closed or a depressed position whether operated independently or concurrently with the lower panel. Thus the upper panel P^1 and means for operating the same, may be said to constitute a means whereby 85 to admit air (from above the wing) to the opening, (at 28, Fig. 4) between the rearward side 27^a of the lower panel and the forward side of the wing-zone Z^2 , which is rearward of the open mid-zone of the wing. 90

Having thus described my invention, I claim—

1. In combination, an airplane wing having near each outer end of the wing an opening through the wing extending longitudinally of the wing in an inward direction, each opening having a downwardly and outwardly inclined side whereby the opening is of greater length at its bottom than at its top; and a movable panel for each of said 100 openings for normally closing the same, the panel having adjacent to the inclined side of the opening a downwardly and outwardly inclined side whereby the panel is longer on its bottom edge than on its top edge and is conformably engageable in the opening; said panels being movable for unclosing the openings for relieving air pressure on said wing when the airplane is in upward flight and causing passage of the air downwardly 110 through said openings and in an outward direction beneath the under surface of the wing for lifting the wing. 105

2. In combination, an airplane wing having near each outer end of the wing an opening through the wing extending longitudinally of the wing in an inward direction, each opening having a downwardly and outwardly inclined side whereby the opening is of greater length at its bottom than at its top; and a movable panel for each of said 115 openings for normally closing the same, the panel having adjacent to the inclined side of the opening a downwardly and outwardly inclined side whereby the panel is longer on its bottom edge than on its top edge and is conformably engageable in the opening, the upper and under surfaces of the panels when in closing position merging with the upper 120 and under surfaces of the wing; said panels 125

being movable for unclosing the openings for relieving air pressure on said wing when the airplane is in upward flight and causing passage of the air downwardly through said 5 openings and in an outward direction beneath the under surface of the wing for lifting the wing.

3. In an airplane wing, in combination, a frame having upper and lower surfacings 10 with a depth-wise distance between them, and also having in a mid-width zone thereof a chamber extending depth-wise as an opening entirely through the wing and dividing the wing into forward and rear zones; a 15 panel having upper and lower surfacings with a depth-wise distance between them, and pivotally connected to the forward zone at the forward edge of its upper surfacings and the rear edge of the upper surfacing of 20 the forward zone; the forward edge of the lower surfacing of the panel being adapted during pivotal movement to dispose itself above and adjacent the rear edge of the lower surfacing of the forward zone, thereby 25 to provide, at all times, a merging of said lower surfacings of the panel and forward zone with each other.

4. In an airplane wing, in combination, a frame having upper and lower surfacings 30 with a depth-wise distance between them, and also having a mid-width opening extending depth-wise entirely through the wing and dividing the wing into forward and rear zones; and a panel having upper 35 and lower surfacings with a depth-wise distance between them, and pivotally connected at the forward edge of its upper surfacings with the rear edge of the surfacing of the forward zone; the forward edge of the lower surfacing of the panel being adapted at 40 times during pivotal movement to dispose itself just above and at other times substantially flush with the rear edge of the lower surfacing of the zone.

5. In an airplane wing, in combination, a frame having upper and lower surfacings 45 with a depth-wise distance between them, and also having a mid-width opening extending depth-wise through the wing and dividing the wing into forward and rear zones; and a panel having upper and lower surfacings with a depth-wise distance between them, and pivotally connected at the forward edge of its upper surfacings with the rear edge of the surfacing of the forward zone.

6. In an airplane wing, in combination, a frame having upper and lower surfacings 50 with a depth-wise distance between them, and also having a mid-width opening extending through the wing and dividing the wing into zones and provided with a downwardly inclined face; and a panel pivotally connected to an edge of the opening and having its downwardly inclined edge oppo-

site to the pivot edge provided with a surface adapted when the panel is open to provide a downwardly inclined passage.

7. In an airplane wing, in combination, 70 a frame having upper and lower surfacings with a depth-wise distance between them, and also having in a mid-width zone thereof a chamber extending depth-wise as an opening entirely through the wing and dividing the wing into forward and rear zones and provided with a rearwardly and downwardly inclined rear face; and a panel being pivotally connected at its forward edge with the rear edge of the forward zone, and having its rear surface downwardly and rearwardly inclined and adapted when the panel is open to provide a rearwardly and downwardly inclined passage.

8. In an airplane wing, in combination, a frame having upper and lower surfacings 85 with a depth-wise distance between them, and also having a mid-width opening extending depth-wise through the wing and dividing the wing into forward and rear 90 zones and provided with a rearwardly and downwardly inclined rear face; and a panel having upper and lower surfacings with a depth-wise distance between them, and pivotally connected at its forward edge with 95 the rear edge of the forward zone, and having its rear surface downwardly and rearwardly inclined and adapted when the panel is open to provide a rearwardly and downwardly flaring passage.

9. In an airplane wing, in combination, a frame having upper and lower surfacings 100 with a depth-wise distance between them, and also having in a mid-width zone thereof a chamber extending depth-wise as an opening entirely through the wing and dividing the wing into forward and rear zones and provided with a rearwardly and downwardly inclined rear face; and a panel having upper and lower surfacings with a depth-wise distance between them, and pivotally connected at the forward edge of 105 its upper surfacings with the rear edge of the surfacing of the forward zone, and having its rear upper surface downwardly and rearwardly inclined and adapted when the panel is closed to engage flat against said rear face of the opening and when the panel is open to provide rearwardly and downwardly diverging surfaces forming a 110 rearwardly and downwardly flaring passage.

10. An airplane wing having for a portion of its length and transversely thereof three zones, viz., a forward zone in fixed relation in and to the wing; a mid-zone 115 hinged on an axis at its forward edge to the rearward edge of said forward zone; a rearward zone having the forward edge thereof overlapping the rearward edge of said mid-zone by a distance of more than 120

one-fourth of the width of said mid-zone, said mid-zone being operable on said forward axis thereof and downwardly from a closed position in which this mid-zone forms an alined continuation of and between the lower surfaces of the forward and rearward zones.

11. In an airplane wing, in combination, a wing-frame with upper and lower surfaces and having longitudinally thereof a chamber-form wing-opening in a mid-width zone thereof, and having said wing-opening extending farther rearward on said lower surface than on said upper surface; an upper panel operably joining said upper surface at the forward side of said wing-opening, and a lower panel operably joining said lower surface at the forward side of said wing-opening, said upper panel being arranged to swing downwardly into said wing-opening and said lower panel to swing downwardly below said wing-opening to thereby increase the lifting effect of said lower panel.

12. In an airplane wing, in combination, a wing-frame with upper and lower surfaces and having longitudinally thereof a chamber-form wing-opening in a mid-width zone thereof, and having said wing-opening extending farther rearward on said lower surface than on said upper surface; an upper panel operably joining said upper surface at the forward side of said wing-opening, and a lower panel operably joining said lower surface at the forward side of said wing-opening; and means connected and arranged for operating said panels to swing said upper panel downwardly into said wing-opening and simultaneously to swing said lower panel downwardly below said wing-opening to thereby increase the lifting effect of said lower panel and to also open a passage for a down-flowing current of air rearward of the two panels, substantially as and for the purpose set forth.

13. An airplane wing comprising a framework enclosed between spaced-apart upper and lower wing-surfaces, and having for a portion of its length and transversely thereof of three zones, viz., a forward zone in fixed relation in and to the wing; an operably-supported mid-zone hinged at its forward edge to the rearward edge of said forward zone; and a rearward zone in a fixed relation to the wing and having the forward edge thereof overlapping the rearward edge of said mid-zone, and said mid-zone being of a width to underlap said rearward zone by a distance of between one-fourth and one-half the width of the mid-zone.

14. An airplane wing comprising a framework enclosed between spaced-apart upper and lower wing-surfaces, and having for a portion of its length and transversely there-

of three zones, viz., a forward zone in fixed relation to the wing; a mid-zone hinged at its forward edge to the rearward edge of said forward zone and hinged on an axis contiguous to said upper surface; and, a rearward zone in a fixed relation to the wing and having the forward edge thereof overlapping the rearward edge of said mid-zone, and said mid-zone being of a width to underlap said rearward zone by a distance of more than one-third the width of said mid-zone.

15. An airplane wing comprising a framework enclosed between spaced-apart upper and lower wing-surfaces, and having for a portion of its length and transversely thereof of three zones, viz., a forward zone in fixed relation to the wing; a mid-zone hinged at its forward edge to the rearward edge of said forward zone and hinged on an axis contiguous to said upper surface; and, a rearward zone having the forward edge thereof overlapping the rearward edge of said mid-zone, and said mid-zone being of a width to underlap said rearward zone by a distance greater than the spaced-apart distance of said upper and lower wing surfaces.

16. In an airplane wing, in combination, a frame-work having upper and lower surfacings with a depth-wise distance between them, and also having in a mid-width zone thereof a chamber extending depth-wise as an opening through the wing; a lower mid-zone panel operably joining at its forward edge the rearward edge of the lower-zone surfacing of the wing which is forward of said chamber and wing opening, said panel when closed forming a continuation of such lower and forward wing-zone surfacing and thereby closing said wing opening; means for depressing said panel by lowering the rearward edge thereof without unjoining the forward edge thereof; an upper mid-zone panel operably joining at its forward edge the rearward edge of the upper-zone surfacing of the wing which is forward of said chamber and wing-opening; and, means connecting said upper and lower mid-zone panels for the concurrent operation of each one with the other.

17. An airplane wing comprising a framework enclosed between spaced-apart upper and lower wing-surfaces, and having for a portion of its length and transversely thereof of three zones, viz., a forward zone in fixed relation to the wing, an open mid-zone, and a rearward zone in fixed relation and to the wing; a passage-way controlling pressure-plane constituting when closed a mid-zone lower panel of the under wing-surface, said panel being closed against the passage of air at its forward side, and operable downwardly for the passage of air at its rearward side; an inclined lifting surface between the upper and lower wing-surfaces;

and means coactive with the pressure-plane for admitting air from above the wing to said inclined lifting-surface on the operating of the pressure-plane in a direction for raising the wing, for thereby combining the lifting effects of said inclined surface with said pressure-plane.

18. An airplane wing comprising a frame-work enclosed between spaced-apart upper and lower wing-surfaces, and having for a portion of its length and transversely thereof three zones, viz., a forward zone in fixed relation to the wing, an open mid-zone, and a rearward zone in fixed relation 10 to the wing; a movable pressure-plane constituting when closed a mid-zone lower panel of the under wing-surface, said panel being closed against the passage of air at its forward side, and operable downwardly 15 for the passage of air at its rearward side; an inclined lifting surface between the upper and lower wing-surfaces, and on the rearward side of said open mid-zone, and having its forward edge above a medial line 20 of said lower panel; and, means coactive with the pressure-plane for admitting air from above the wing and forward of said medial line to said inclined lifting-surface on the operating of the pressure-plane in 25 30 a direction for raising the wing, for thereby combining the lifting effects of said inclined surface with said pressure-plane.
19. In an airplane wing, in combination, a frame-work having upper and lower surfaces with an interior space between them, and also having in a mid-width zone thereof a chamber extending depth-wise entirely through the wing; a panel operably joining at its forward edge the rearward edge 35 40 of the lower zone surfacing of the wing which is forward of said chamber and wing opening, said panel when closed forming an alined continuation of such lower and forward wing-zone surfacing and thereby closing said wing opening; means connected and operable for depressing the panel by lowering the rearward edge thereof without unjoining the forward edge thereof; and, means for reducing the effective up- 45 50 ward-movement-resisting area of the up-

per wing-surface concurrently with said depressing of the panel.

20. In an airplane wing, in combination, a frame-work having upper and lower surfaces with an interior space between them, and also having in a mid-width zone thereof a chamber extending depth-wise as an opening through the wing; a panel operably joining at its forward edge the rearward edge of the lower zone surfacing of 60 the wing which is forward of said chamber and wing opening, said panel when closed forming a continuation of such lower and forward wing-zone surfacing and thereby closing said wing opening; means for depressing the panel by lowering the rearward side thereof without unjoining the forward edge thereof; and, means for admitting an air current through said wing opening and directing this current under the 70 wing and to the rearward of said panel, on the depressing of the panel.

21. In an airplane wing, in combination, a frame-work having upper and lower surfaces with an interior space between them, and also having in a mid-width zone thereof a chamber extending depth-wise as an opening through the wing; a panel operably joining at its forward edge the rearward edge of the lower zone surfacing of 75 the wing which is forward of said chamber and wing opening, said panel when closed forming a continuation of such lower and forward wing-zone surfacing and thereby closing said wing opening; means for depressing the panel by lowering the rearward edge thereof without unjoining the forward edge thereof; and, means for admitting an air current through said wing opening and directing this current under the wing 80 and to the rearward of said panel, on the depressing of this panel, such means comprising an upper panel operably joining at its forward edge with the rearward edge of an upper and forward wing-zone surface.
